[57] CLAIM

The ornamental design for a collapsible toy, as shown and described.

DESCRIPTION

FIG. 1 is a top plan view of a collapsible toy showing our new design;

FIG. 2 is a bottom plan view of a collapsible toy thereof; FIG. 3 is an elevational view of one side of the toy object, the other side being a mirror image thereof;

FIG. 4 is an elevational view of the collapsible toy, the toy object having been rotated from the position shown in FIG. III by approximately 30° about an axis passing through the top and bottom ends of the toy object;

FIG. 5 is a front perspective view showing the top, front and side of the collapsible toy, the bottom, rear and other side being a mirror image thereof;

FIG. 6 is a front perspective view showing the top and side of the collapsible toy, the bottom and other side being a mirror image thereof;

FIG. 7 is a top plan view showing the collapsible toy in an alternate configuration;

FIG. 8 is a bottom plan view showing the collapsible toy in the alternate configuration;

FIG. 9 is an elevational view of the front of the collapsible toy in the alternate configuration, the back side being a mirror image thereof;

FIG. 10 is a front perspective view showing the front and side of the collapsible toy in the alternate configuration; and, FIG. 11 is a rear perspective view showing the rear and side of the collapsible toy in the alternate configuration.
